UNITED STATES PATENT OFFICE.

WILLIAM W. TRINKS, OF BRIDGEPORT, CONNECTICUT, ASSIGNOR TO PULLCLEAN MANUFACTURING CORPORATION, OF BRIDGEPORT, CONNECTICUT, A CORPORATION OF DELAWARE.

LAUNDERING MACHINE.

Application filed March 29, 1924. Serial No. 702,985.

This invention relates to laundering machines and comprises certain improvements upon the machine made the subject of pending application Serial No. 516,806, filed November 21, 1921.

The machine of the aforesaid application comprises a washing tank having rotary scrubbing brushes mounted therein, a bar for detachable connection with a towel, and a pair of endless carrier belts having means for engaging the opposite ends of said bar and being operative in a path to carry the bar and connected towel through the washing tank between the scrubbing brushes therein. The connection between these carrier belts and the bar in said prior machine is a loose one, effected by inwardly projecting arms on the carrier belts loosely engaging the ends of the bar within open notches therein, and it has been found in practice that when the bar is being moved by the carrier belts between the rotary scrubbing brushes in the tank it sometimes happens that the bar becomes disengaged from the carrier belts by the action of certain of the brushes which are rotated in the direction of movement of the bar. To prevent such disengagement of the bar from the carrier belts has been one of the objects of my present invention, and I accomplish this in a preferred form of the invention by locating a plurality of wires within the tank in position to engage the bar during its passage therethrough and yieldingly hold or maintain it in operative connection with the carriers.

A further feature of my present invention relates to a means for maintaining the towel, and particularly the rear loose end thereof, in a laterally spread and smooth condition in its passage between the brushes in the tank. It was found in practice that the rear loose end of the towel, being unsupported in its passage between the successive pairs of brushes, would drop downward at such points and have a tendency to wrinkle and fold laterally on itself, thus preventing all parts thereof being directly acted upon by the brushes. To avoid this tendency to wrinkle and assure the towel being maintained in a spread condition at its rear end has therefore been a further object of the invention, which object I attain by pro-

viding supports for the towel, preferably in the form of rollers, between the several pairs of brushes.

Other objects and advantages of the invention will be referred to in the detailed description of the invention which follows.

Referring now to the accompanying drawings, in which I have shown only such part of a complete laundering machine as is necessary for the illustration of the present invention—

Figure 1 is a top plan of the front end of a laundering machine comprising the washing tank and the towel-supporting reel, from which latter the towel is unwound when drawn through the tank.

Fig. 2 is a vertical longitudinal section through the tank and associated parts, with the towel supporting reel in elevation.

Fig. 3 is an enlarged detail showing the detachable connection between the towel bar and carrier belts.

Fig. 4 is an inner end view of one of the bar engaging arms on the carrier belts.

Similar reference characters indicate like parts in the several figures of the drawings.

The washing tank, indicated at 1, may be of any usual or suitable construction, and as here shown is supported in a raised position from the floor on legs 2.

Mounted within this tank are two sets of rotary scrubbing brushes, the brushes of one set, indicated at 4, being arranged immediately above those of the other set, indicated at 5, whereby the brushes of each set will be directly opposed for cooperation in acting upon the opposite sides of a towel being drawn or fed therebetween.

Each of these brushes is mounted on a shaft 6 which is journaled at its opposite ends in suitable journal boxes slidably mounted in vertical guides 8-8 on the opposite inner walls of the tank, the brushes of each set being vertically adjustable with respect to those of the other for the purpose of taking up wear of the brushes and keeping them in proper working relation.

The two sets of brushes are adapted to be operated in a manner whereby their adjacent opposed faces will move or rotate in opposite directions relatively to each other, this movement of the same obviously resulting in a more efficient scrubbing action on

the interposed towel. Any suitable means may be employed for operating the brushes in the manner stated, one desirable means being that disclosed in my aforesaid application, Serial No. 516,806. As here shown, like in my aforesaid application, the brushes in both the washing and rinsing tanks are operated by like connections from a main drive shaft 10 journalled in brackets 11 on one side of the tank 1. These connections comprise a shaft 12 which is journalled in suitable bearings on the opposite upper edges of the tank and operated from the drive shaft 10 through bevel gears 14. Fixed to this shaft 12 is a pinion 40 which meshes with and drives a large spur gear 41 mounted on a shaft 49. This gear 41 in turn meshes with and drives two pinions 42 and 43, the pinion 42 being in driving connection with the upper set of brushes and the pinion 43 being in driving connection with the lower set of brushes.

The pinion 42, as here shown, is fixed on the shaft 6 of the end brush of the upper set, and this shaft is in operative driving connection with the several other shafts of the same set through sprockets and connecting chains, 44 and 45 respectively, as clearly shown in Fig. 1, while the pinion 43 is fixed to a shaft 46 journalled in suitable bearings on the inner walls of the tank, which shaft adjacent its opposite or rear end is in operative driving connection with the several shafts of the lower set of brushes through sprockets and connecting chains, 47 and 48 respectively, also as clearly shown in Fig. 1. It will thus be clear that the two sets of brushes, driven from the gear 41 through the connections described, will be caused to rotate with their adjacent opposed faces moving in opposite directions relatively to each other for the purpose referred to.

The towels to be laundered are preferably in roll form, the same being wound about a hollow tube or mandrel. This permits of the towels being conveniently mounted for rotation on a suitable support in front of the tank 1 and being gradually unwound therefrom as their front or leading ends are advanced through the machine. Preferably I provide a reel 50 for carrying a plurality of towels, which is mounted on a shaft 51 journalled at its opposite ends in standards 52—52 secured in stationary position on the floor or other support. The reel is here shown as provided with a plurality of spindles 300 which are adapted to be passed through the tubes on which the towels are wound for the purpose of rotatably mounting the towels on the reel.

From the reel 50, the free end of a towel supported thereon is led to a position at the upper front end of the tank to be engaged by the towel feeding means, which latter

comprises a pair of endless carrier belts 53—53, here shown in the form of sprocket chains, which are spaced apart a distance slightly greater than the width of the towel and mounted on a series of suitably supported sprocket wheels, some of which serve as guides and others of which serve as drive wheels, these latter being actuated through suitable gearing from the main drive shaft 10 as in the aforesaid application. The general path of these carrier belts is indicated by a broken line in Fig. 2, wherein they are shown as entering downwardly into the tank at its front end, thence moving in a horizontal path in a plane between the upper and lower sets of brushes to the rear end of the tank, and from thence passing upwardly and out of the tank.

As a means for effecting connection of the towel *t* with the carrier belts to be drawn by the latter through the machine, the towel is provided at its front end with a loop 54 through which is passed a flat bar 55 with its ends projecting slightly beyond the opposite edges of the towel for connection with the carrier belts, these latter being provided at predetermined points with inwardly projecting forked arms 56 having pins 57 for engaging the projecting ends of the towel bar within notches 58 therein (see Figs. 3 and 4).

When the end of a towel is thus connected with the continuously moving carrier belts at the upper front end of the tank, it is drawn by them over the guide rolls 59 and 60 to a point above the washing chamber, thence downwardly into the chamber and beneath a guide roll 61, from which latter it is advanced between the opposed upper and lower sets of rotating brushes to a point adjacent the rear end of the chamber, where it is carried about a guide roll 62 and from thence upwardly and about a guide roll 63 to a wringer.

The several pairs of feed-chain driving sprocket wheels which are mounted on the washing tank are indicated at 70—70 and 71—71, the wheels 70—70 being mounted on a shaft 74 which is journalled on the upper edge of the tank and driven from the shaft 10 through the bevel gearing 75, and the wheels 71—71 being mounted on the shaft 12 at the rear upper end of the washing tank which is driven from the shaft 10 through the bevel gearing 14. The several other sprocket wheels mounted on the tank and on the supporting legs thereof, indicated at 78, about which the chains pass, are merely guides which cooperate with the driving sprockets for directing the movement of the chains in their proper paths.

As hereinbefore mentioned, when the towel bar 55 is being drawn between the upper and lower sets of scrubbing brushes, the upper set of brushes, rotating in the di-

rection of movement of the bar, has a tendency to disengage the latter from the arms 56 on the carrier belts, in which event there is of course a liability of breakage or other damage to the parts. To avoid this I have stretched a plurality of parallel wires 15 between the upper and lower sets of brushes in position to yieldingly engage the upper side of the bar 55 and produce a braking action thereon sufficient to maintain it in its operative engagement with the carrier belt arms 56 when being advanced between the brushes. These wires may be supported in any suitable or desired way. As shown, they are stretched over positioning cross bars 16, 16, fixed within the tank adjacent the front and rear ends of the series of brushes, and at their opposite ends are anchored to a second pair of cross bars 17, 17, fixed within the tank adjacent its top. In order that the tension of these wires may be properly adjusted the wires are provided with screw-adjusted tightening devices 18 at one end thereof as shown.

During the passage of a towel between the brushes, the rear loose end of the same, being unsupported between the successive pairs of brushes, drops down between the latter. When this happens the said loose end, as hereinbefore stated, has a tendency to wrinkle and fold laterally on itself. To avoid this I have located a pair of small suitably journalled rolls 20, 20, between each pair of brushes, which are arranged to engage the towel from the lower and upper sides thereof, the lower roll serving to support the towel and the upper roll cooperatively therewith serving to maintain the interposed towel in its normal laterally spread condition. With this arrangement of parts, it has been found that towels will be maintained in a smooth and unwrinkled condition throughout their length during their passage through the washing tank.

The bar engaging wires 15 extend between the upper and lower sets of rolls 20, by which they are maintained in their normal straight position and against vertical deflection. In order that the rolls of the upper and lower sets may be in close relation to each other—notwithstanding the interposition of the wires 15 therebetween—for cooperation in acting upon the interposed towels, the rolls of the upper set are each formed with a series of circumferential grooves 22 in which the wires are received as shown. These grooves also serve to maintain the wires in their laterally spaced relation, as will be clear by reference to Fig. 1.

As a means for guiding the towels in their passage through the tank and preventing undue lateral deflection of the same, I have provided a plurality of pairs of guides for engagement with the opposite edges of the towels. One of these pairs of guides is lo-

cated adjacent the front end of the tank and a second pair adjacent the rear end. Only one member of each pair is shown in Fig. 2, but such illustration is sufficient, as both members of each pair are identical. 70

Each guide member of the front pair comprises a short vertically arranged bar 25 pivoted adjacent its upper end, at 26, to an ear 27 of a bracket plate 28 fixed to the front end of the tank. The upper end of 75 these bars extend into the path of movement of the towel bar 55 where the latter projects beyond the edges of the towel, but this is provided for by the pivotal support of the bars which permits them to yield when engaged by the towel bar and to thereafter automatically return to their normal position following the passage of the towel bar thereover.

The second pair of guides which are those 80 located at the rear end of the tank, are of similar construction and operation to the first pair in that each member 30 is pivotally connected at 31 to a supporting bracket 32 fixed to the rear wall of the tank, but 85 the guide members of this second pair are horizontally arranged and this makes necessary the provision of a stop pin 33 for engagement with the rear end of each guide to hold it in its normal towel guiding position as shown. In operation, when the towel bar strikes the ends of the guides 30, the latter will raise and permit of the passage of the towel bar beyond the same, after which they will gravitate back to their normal position with their rear ends engaging the stop pins 33. 95

What I claim is:

1. In a machine of the class described, a washing tank, scrubbing brushes therein, a 105 towel connecting bar, carrier belts having means loosely connecting with said bar and movable in a path to carry the latter and connected towel through the tank and in operative relation to the brushes therein, and means for engaging the said towel bar in its passage through the tank and maintaining its connection with the carrier belts. 110

2. In a machine of the class described, a 115 washing tank, a pair of opposed scrubbing brushes therein, means for rotating said brushes in opposite directions, a towel connecting bar, carrier belts having means loosely connecting with said bar and movable in a path to carry the latter and connected towel through the tank and between the brushes therein, and means engaging said towel bar in its passage through the tank and maintaining its connection with the carrier belts. 120

3. In a machine of the class described, a washing tank, scrubbing brushes therein, a 125 towel connecting bar, carrier belts having means loosely connecting with said bar and movable in a path to carry the latter and 130

connected towel through the tank and in operative relation to the brushes therein, and a wire extending lengthwise of the tank engaging the said towel bar in its passage 5 through the latter and maintaining its connection with the carrier belts.

4. In a machine of the class described, a washing tank, two sets of opposed rotary scrubbing brushes therein, means for rotating 10 the two sets of brushes in opposite directions relatively to each other, a towel connecting bar, carrier belts having means loosely connecting with said bar and movable in a path through the tank to carry 15 the bar and connected towel between the two sets of brushes therein, and a series of wires extending lengthwise of the tank engaging the towel bar in its passage through the latter and maintaining its connection 20 with the carrier belts.

5. In a machine of the class described, a washing tank, scrubbing brushes therein, a towel connecting bar, carrier belts having means loosely connecting with said bar and 25 movable in a path to carry the latter and connected towel through the tank and in operative relation to the brushes therein, a wire extending lengthwise of the tank engaging the said towel bar in its passage 30 through the latter and maintaining its connection with the carrier belts, and a series of rollers engaging with and holding the wire in position in the path of travel of the towel bar.

35 6. In a machine of the class described, a washing tank, two sets of opposed rotary scrubbing brushes therein, means for rotating the two sets of brushes in opposite directions relatively to each other, a towel connecting bar, carrier belts having means loosely connecting with said bar and 40 movable in a path through the tank to carry the bar and connected towel between the two sets of brushes therein, and a series of 45 grooved rollers engaging with and holding the wires in position in the path of travel of the towel bar.

50 7. In a machine of the class described, a washing tank, a plurality of pairs of opposed rotary scrubbing brushes therein, carrier belts operative to draw a towel through the tank between the pairs of brushes therein, and rollers intermediate of the pairs of brushes for engaging the towel and maintaining it in a smooth condition during its 55 passage between said brushes.

50 8. In a machine of the class described, a washing tank, a plurality of pairs of opposed rotary scrubbing brushes therein, a carrier operative to draw a towel through the tank between the pairs of brushes therein, and pairs of rollers intermediate of the pairs of brushes for engaging the towel at the lower and upper sides thereof and main-

taining it in a smooth condition during its 65 passage between said brushes.

9. In a machine of the class described, a washing tank, a plurality of pairs of opposed rotary scrubbing brushes therein, a towel connecting bar, carrier belts having 70 means loosely connecting with said bar and movable in a path to carry the latter and connected towel through the tank between the pairs of brushes therein, pairs of rollers intermediate of the pairs of brushes for 75 engaging the towel at the lower and upper sides thereof and maintaining it in a smooth condition during its passage between the brushes, a series of wires extending lengthwise of the tank between the upper and 80 lower sets of brushes and rollers and operative to engage the towel bar in its passage through the tank and maintain its connection with the carrier belts.

10. In a machine of the class described, 85 a washing tank, scrubbing brushes therein, a towel connecting bar projecting at its ends beyond the opposite sides of the towel, carrier belts operative to engage said bar and draw the same and connected towel through 90 the tank between the brushes therein, and guides for engaging the opposite sides of the towel normally extending into the path of the projecting ends of the towel bar, said guides being pivoted whereby they may 95 be moved from the path of the towel bar by the engagement of the latter therewith.

11. In a machine of the class described, a washing tank, means operative to draw a 100 towel through the tank, a scrubbing brush mounted in the tank for engagement with the towel and being movable in the direction of feed of the towel, and a plurality of wires interposed between the brush and the towel.

12. In a machine of the class described, a washing tank, two sets of opposed rotary scrubbing brushes therein, means operative to draw a towel through the tank between 110 the two sets of brushes therein, one of said sets of brushes being rotatable in the direction of feed of the towel, and a plurality of wires interposed between the last named set of brushes and the towel.

13. In a machine of the class described, 115 a washing tank, two sets of opposed rotary scrubbing brushes therein, means operative to draw a towel through the tank between the two sets of brushes therein, one of said sets of brushes being rotatable in the direction of feed of the towel, a plurality of wires interposed between the last named set of brushes and the towel, and rollers intermediate of the brushes of one set for supporting engagement with the towel.

In testimony whereof I affix my signature.

WILLIAM W. TRINKS.
